Primary Examiner — Michael C Stout*Assistant Examiner* — Emmett Cygnet(74) *Attorney, Agent, or Firm* — Bartholomew Law PC; Michael Bartholomew(57) **CLAIM**

The ornamental design for a laser hair removal device as shown and described.

DESCRIPTION

FIG. 1 is a front, left and top perspective view of a laser hair removal device, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the laser hair removal device that form no part of the claimed design.

1 Claim, 8 Drawing Sheets(56)
